UNITED STATES PATENT OFFICE.

VERNON A. JOY, OF NEW YORK, N. Y.

DEVICE FOR DISPLAYING THE COVERING OF BOXES AND OTHER CONTAINERS.

1,380,148.

Specification of Letters Patent. Patented May 31, 1921.

Application filed March 12, 1921. Serial No. 451,857.

To all whom it may concern:

Be it known that I, VERNON A. JOY, a citizen of the United States, residing at New York, in the county of New York and State 5 of New York, have invented a new and useful Improvement in Devices for Displaying the Covering of Boxes and other Containers, of which the following is a specification.

This invention relates to devices for displaying the coverings of boxes or containers in such a manner as to simulate the actual boxes or containers.

In the sale of some articles, the covering or ornamentation of the box or container 10 plays an important part, since the containers are frequently selected with the view of matching or harmonizing with other decorations. For example, boxes containing hairpins are frequently bought for the purpose of having the box create an ornamental or artistic appearance on a dresser or in a room, and consequently salesmen of such 15 articles are obliged to carry with them many different boxes in order to demonstrate their wares to dealers or retailers and these boxes occupy much space, and frequently become 20 broken or injured in transit. Merely carrying samples of the covering material is not satisfactory, since the prospective purchasers 25 cannot get a good idea as to the appearance of the boxes or containers by merely inspecting these samples.

The objects of this invention are to provide a device of this kind in which a sample 30 of the covering material is used and in which the flat sample is so cut and lined as to represent the actual container or box; also to improve devices of this kind in the other respects hereinafter specified.

40. In the accompanying drawings:

Figures 1 and 2 represent devices embodying the invention for displaying the coverings of boxes or containers.

Fig. 3 shows a blank made of the actual 45 covering material to be used before the same is lined.

Fig. 4 shows the blank after the same is lined.

Fig. 5 shows a representation of the contents of the box before the same is placed 50 in operative relation to the lined blank.

The device embodying the invention, which is shown in the accompanying drawings, is made of two substantially flat parts, 55 to wit, a lower part A, which is made of the material with which the boxes or con-

tainers are covered and which is cut in such a manner that this part will form the basis for a representation, preferably of a box standing on a cover or lid, the outer edges 60 of the part A corresponding to the outer edges of the representation of the box and cover, and an upper part B, which is preferably made of paper and on which is preferably shown a representation of the interior and contents of the box. Fig. 3 shows the blank which is cut to form the lower part A of the device shown in Fig. 1. In order to have the device simulate the appearance of a box and cover therefor, lines 70 are preferably formed on the blank, either by printing, drawing, or other means to make the lower part A appear like a perspective view of a box. In the construction shown in Figs. 1 and 4, lines *a* represent the 75 lower edges of the box, lines *b* represent the upper edges of the cover upon which the box is represented as standing, and line *c* represents one of the upright edges of the cover. In the construction shown in Fig. 2, 80 similar lines are used and also a line *d* which represents an upright edge of the box. These lines are preferably drawn substantially parallel to certain edges of the blank to produce the desired appearance. 85

The upper part or member B is preferably either printed or otherwise formed to represent the upper edge, and the interior of the box, with or without the contents of the box. This representation in the construction shown, may include a lower portion or flap *g* which is arranged in back of the lower part A of the device, and which may, if desired, form a connection between the upper and lower parts of the device, a part 90 *h* which represents the part of the box which is engaged by the cover and which extends above the covering material of the box, and a representation *i* of the contents of the box. If desired, lines *k* may also be used to represent dividing walls in the box, as shown in Figs. 1 and 5. The part B is preferably made of material used on the interior of the box. For example, if the inner portions of the boxes are generally white, the upper 95 part of the device may be printed on plain, white paper, the lines *l* thereof representing the upper edges of the inner portions of the box. The upper part B is preferably cut along the outer edges of the representation 100 of the contents and the two parts A and B are then pasted or otherwise secured in op-

erative relation to each other, as shown in Figs. 1 and 2, thereby producing a representation of a box standing upon its cover.

The device described has the advantages 5 that it can be inexpensively produced since the upper portions B can be printed and cut in large quantities and the lower parts A can be also cut and printed at very little expense. The two parts of the device 10 can then be placed in operative relation to each other by pasting the two parts on a page of a book, catalogue or other flat display device, and the device then occupies very little space. By having the flap g of 15 the upper part of the device extend under the lower part, the two parts of the device can be secured together, but if the devices are to be pasted in a book, the flap may be omitted if desired. In looking at the device, 20 a correct idea can be obtained as to the appearance of the actual boxes and if it is desired to inspect the quality, color or design of the covering material of the box, this can be done since the material from 25 which the part A of the device is made is the actual covering material which is to be used on the boxes, and not merely a lithographed copy or imitation thereof. A large number of devices of this kind can be pasted 30 or secured in a book and the necessity of carrying the actual boxes or containers is eliminated.

I claim as my invention:

1. A device for displaying the covering 35 material of containers, comprising a flat part made of the covering material which it is proposed to use on the containers and which is cut and lined to represent the container, and a flat part arranged above said first mentioned part and which is provided with a representation of the interior of the container.

2. A device for displaying the covering 45 material of containers, comprising a flat part made of the covering material which it is proposed to use on the containers and which is cut and lined to represent the con-

tainer and the cover therefor out of engagement with the upper portion of the container, and a flat part arranged in operative 50 relation to the upper edge of said first mentioned part and which is provided with a representation of the interior of the container.

3. A device for displaying the covering 55 material of boxes, comprising a sheet made of covering material which it is proposed to use on the boxes and which is cut and lined to represent a box standing on the cover of a box, and a sheet arranged above said first mentioned sheet and which is provided with a representation of the interior of the box and which is arranged above the upper edge of said first mentioned sheet, to form therewith a representation of an open box standing 60 on its cover.

4. A device for displaying the covering 65 material of boxes comprising a sheet made of covering material which it is proposed to use on the boxes and which is cut in such a 70 manner that the cut edges thereof represent the outer edges of a perspective view of a box and cover, and which is provided with lines representing other edges of a box and cover, and a sheet provided with a representation of the interior of a box and 75 adapted to be secured in proximity to the edge of said first mentioned sheet which represents the upper edge of the box.

5. A device for displaying the covering 80 material of containers, comprising a part made of the covering material which it is proposed to use on the containers and which is cut and lined to represent the container, and a part arranged above said first mentioned part and which is provided with a representation of the interior of the container and which has a portion which is 85 adapted to be secured to the rear face of said first mentioned member, said two parts 90 being arranged substantially in the same plane whereby the device may form a part of a page of a book.

VERNON A. JOY.
